United States Patent Office.

R. W. SHRINER, OF WOODLAND, MICHIGAN.

Letters Patent No. 60,946, dated January 1, 1867.

IMPROVEMENT IN CHURNS.

The Schedule referred to in these Letters Patent and making part of the same.

TO ALL WHOM IT MAY CONCERN:

Be it known that I, R. W. SHRINER, of Woodland, in the county of Barry, and State of Michigan, have invented a new and improved Churn; and I do hereby declare that the following is a full, clear, and exact description thereof, which will enable others skilled in the art to make and use the same, reference being had to the accompanying drawings, forming part of this specification, in which—

Figure 1 represents a front view of the same, partly in section.

Figure 2 represents a vertical cross-section, taken on a plane indicated by the line $z z$, fig. 1.

Similar letters of reference indicate like parts.

This invention relates to an improvement in the power by which a churn is worked, and has for its object the giving to the dasher an up and down motion as well as an alternate horizontal rotary motion; and the invention consists not only in the peculiarity of this motion, by which the butter is much easier made than by any other known motion, but also in the construction of the machinery by which the above-mentioned object may be attained. The construction of the power must be such that any sized churn may be worked by it without interfering with its efficiency.

The frame A, which is made of any suitable material, and strong enough to carry the machinery which forms part of my invention, supports the horizontal driving-shaft B. To one end of this shaft is attached the main driving-wheel C, the surface of which is perforated with a number of set-holes, α , into one of which, according to the length of stroke required, the pin b is inserted. A block, c , which turns loosely around the pin, operates the slide D up and down; that is to say, when the wheel C is turned by means of the crank E, it carries the block c around, and as the latter is enclosed in a horizontal groove within the slide D, it will raise or lower the said slide, which is again guided by and between two uprights, d . The main wheel C, is a cog-wheel, as seen in the drawings, and turns the pinion e which is attached to one end of the shaft f , and thus the balance-wheel F is turned, which also is attached to the shaft f . To the lower end of the slide D, but so that it may freely turn within it, is firmly attached the screw-shaft g , which passes at its lower end through a small board, D', forming part and being an extension of slide D, and thus the screw-shaft g is well guided. Just below the board D' the dasher-shaft h is attached to the shaft g by means of a set-screw, as seen in the drawings, and the dasher G will consequently follow the movements of the slide D and the screw g . Into the frame A is firmly imbedded the nut i , through which the screw g passes, and as the thread on the latter is very much elongated, so as to make about one revolution to a length equal to two or three of its diameters, the screw will when pulled through the nut i rotate and reverse its direction as it is pulled up or pushed down. Thus the dasher will receive an up and down motion as well as an alternate horizontal rotary one; and as by the same the cream is stirred much better than by the ones heretofore used, butter will evidently be quicker made. The set-holes α , in the wheel C, permit the adapting of the machine to larger or smaller churning, and as the shape of the churn or dasher does not require to be of a particular kind, the machine can be adapted to almost every kind and size of churning now in use. The churn H is held in place by a lever, K, which is pivoted to the frame A, as seen in the drawings.

Having thus described my invention, what I claim as new, and desire to secure by Letters Patent, is—

The screw g , and its combination with the nut i , slide D, and driving-wheel C, constructed as shown for the purpose of imparting the aforesaid motion to the dasher G.

The above specification of my invention signed by me this 16th day of June, 1866.

R. W. SHRINER.
